UNITED STATES PATENT OFFICE.

EDSON L. CANNON, OF CLEVELAND, OHIO.

DESIGN FOR A GREASE-CUP.

42,911.

Specification for Design.

Patented Aug. 20, 1912.

Application filed June 13, 1912. Serial No. 703,573. Term of patent 7 years.

To all whom it may concern:

Be it known that I, EDSON L. CANNON, a citizen of the United States, and resident of Cleveland, in the county of Cuyahoga and State of Ohio, have invented a new, original, and ornamental Design for a Grease-Cup, reference being had to the accompanying drawing, forming part thereof.

In the figures Figure 1 is a front elevation of a grease cup showing my new design; Fig. 2 is a plan view thereof; Fig. 3 is a bottom view thereof.

I claim:

The ornamental design for a grease cup, as shown.

In testimony whereof, I hereunto set my hand this 29th day of May 1912.

EDSON L. CANNON.

In presence of—

GEO. S. COLE,
Wm. M. MONROE.
